UNITED STATES PATENT OFFICE

HAROLD F. PAGET, OF PHILADELPHIA, PENNSYLVANIA, ASSIGNOR TO HAINES HOSIERY MILLS INC., OF PHILADELPHIA, PENNSYLVANIA, A CORPORATION OF PENNSYLVANIA

LATCH HOOK WELT BAR AND LATCH OPENING MEANS THEREFOR

Application filed January 17, 1930, Serial No. 421,547. Renewed August 6, 1931.

This invention relates to latch hook welt bars for turning the welts incident to knitting of stocking legs on flat hosiery machines; and also to means for opening the hook latches of such bars in preparation for engaging the hooks with the initial course of loops on the needles of the machine in starting the leg blanks.

Welt bars of the kind now generally employed, are provided with latchless hooks; and after turning of the stocking welts, it is necessary to swing the bar upwards and inwards relative to the needles of the machine to release the hooks from the fabric. This is a very exacting procedure, and very difficult of accomplishment in the event of disalignment between the needles and welt bar hooks due to either or both being bent or slightly misshapen. Attempts have been made heretofore to use welt bars with latched hooks, similar to ordinary latched knitting needles, in lieu of the plain hook variety by reason of their facility to close automatically incident to withdrawal from the fabric with obviation of the necessity for swinging the bars as aforesaid; but the advantage thus gained was offset by the difficulty encountered in subsequently opening the hook latches to prepare the welt bars for re-use.

My present invention is directed toward overcoming the difficulty just referred to, through provision, on the one hand, of a welt bar with latched hooks whereof the latches lend themselves to ready opening, and, on the other hand, through provision of means more particularly adapted to knitting machines, by aid of which the hook latches of the welt bar are simultaneously opened in readiness for immediate application to the initial course of the fabric on the needles of the knitting machine in starting new stocking legs.

With reference to the drawings, Fig. I is a fragmentary cross sectional view of a flat stocking knitting machine conveniently embodying my invention.

Fig. II is a fragmentary plan view of the organization shown in Fig. I.

Figs. III, IV and V are detail sectional views, on a larger scale, showing successive

steps incident to opening the latches of the welt bar hooks; and,

Fig. VI is an enlarged perspective view of one of the latched welt bar hooks.

The knitting machines chosen for the purposes of illustration herein is of a well known commercial type designed for production of full fashioned hosiery, one of its needle bars being indicated at 10, the cooperating sinkers at 11, the arm for moving the needle bar vertically relative to said sinkers at 12, the rock shaft for said arm at 13, and a pair of the spaced cross frames which afford journal support to said rock shaft at 14. As usual, the welt bar end guideways, designated by the numeral 15, are rigidly secured transversely of the front "bed", i. e., the channeled longitudinal bed 16 that bridges frames 14 at the top. Also, as usual, the machine is equipped with spaced bracket arms 17 which are bolted to, and reach horizontally outward from the bed 16 and support a roller 18 for taking up the fabric as it is formed on the needles of the bar 10 in the well known manner.

The welt bar designated by the numeral 20 is, generally speaking, of customary construction, except for its hooks 21, which are provided with swinging pivoted latches 22 that extend beyond the ends of said hooks when in closed position, as clearly shown in the perspective illustration of Fig. VI. Such projection of the latches 22 obviously does not interfere with the withdrawal of the hooks 21 from the fabric loops after a stocking welt has been turned on the machine, since said latches will yield readily to automatic closure in a manner characteristic of ordinary latched knitting machine needles. For a purpose later on explained, a supplemental strip 23 is secured to the bottom of the welt bar 20 by means of screws 24, said strip being somewhat longer than the welt bar and extending beyond the ends of the latter, see Fig. II.

The means provided on the knitting machine for opening the latches 22 of the welt bar 20 is comprehensively designated by the numeral 25, and, as shown, comprises a latch engaging element in the form of a bar 26. This latch engaging bar 26 is fixedly sup-

ported crosswise between the welt bar end guideways 15, and, it will be noted, has its forward edge acute and underbeveled as at 27. The latch opening means 25 further embodies a holder means 28 for the welt bar 20 consisting of a pair of end members 29 which are slideable in horizontal recesses 30 at the in sides of the forwardly reaching ends of the guideways 15, said members being held in place by headed screws 31 whereof the shanks extend through motion limiting slots 32 in said guideways. At their outer ends the end members 29 of the holder means 28 are provided with laterally projecting studs 34 which are engaged in bifurcations of lever handles 35 secured to a shaft 36 with journal support at its opposite ends in upward bearing arms 37 of the brackets 17. More particularly from Figs. III-V it will be noted that the end members 29 of the holder means 28 are formed with recesses 38 that afford slightly elevated shoulders 39.

The operation of my invention is as follows:—As the welt bar 20 is removed from the fabric after the turning of a stocking welt in the machine, the holder means 28 is positioned as shown in Fig. III, and said welt bar placed with the ends of its supplemental strip 23 engaging the recesses 38 of the end members 29 of said holder means. When the welt bar 20 is so placed, it will be noted that the rear edge of the supplemental strip 23 rests on the shoulders 39 and the ends of the hooks 21 on the latch engaging element 26. The lever handles 35 are then moved in the direction of the arrow in Fig. III to shift the holder means 28 outward as far as permitted by the screw slots 32, with attendant retraction of the welt bar 20 relative to the latch engaging element 26. The motion thereby imparted is sufficient to draw the ends of the hooks 21 beyond the forward edge of the latch opening element 26. Consequently the welt bar 20 swings on the fulcrum supplied afforded the rear edge of its supplemental strip 23 by the shoulders 39 of the recesses 38 in the end members 28 of the holder means, concurrently with dropping of the hook ends off the element 26, the latches 22 of the hooks 21 being however detained and partly opened incidentally, as shown in Fig. IV. In this action of starting the latches 22 open, the edge 27 of the member 26 engages the latches 22 in the reentrant corner or angle that is afforded between the latches and the ends of the hooks 21 when the latches are closed. The lever handles 35 are thereupon swung in the opposite direction and the holder means 28 shifted inwards relative to the latch opening element 26 as far as permitted by the motion limiting slots 32, as shown in Fig. V. As a result of the last described movement it will be noted that the latches 22 of the welt bar hooks 21 are swung on back and fully opened. The lever hand-

35 are finally swung counter clockwise once more to effect retraction of the welt bar 20 relative to the latch opening element 26 so that said welt bar can be readily removed without danger of the latches being accidentally closed. This final movement has not been illustrated but can be readily understood from Fig. V.

From the foregoing it will be seen that I have provided a very simple and efficient means whereby the latches of the welt bar hooks are simultaneously opened in preparation for re-use of the welt bar at the commencement of each new stocking blank. It is of course to be understood that there is a latch opening means such as described provided for each section of the knitting machine. I

Having thus described my invention, I claim:

1. The combination of a welt bar having loop-engaging hooks with swinging latches projecting beyond the hooks when closed and automatically closing upon withdrawal of the hooks from engagement with fabric loops, a latch-engaging member, and means for moving the welt bar and said member relative to one another transversely and lengthwise of the hooks, thereby first engaging said member with the latches and starting the latches open, and then swinging them on back full open, ready for loop-engagement of the hooks. 95

2. The combination of a welt bar having 100
loop-engaging hooks with swinging latches automatically closing upon withdrawal of the hooks from engagement with fabric loops, and when closed affording a reentrant angle between them and the ends of the hooks, an edged latch-opening member, and means for 105 automatically moving the welt bar and said member relative to one another lengthwise of the hooks, and thereby first engaging the edge of said member with the latches in the angle between them and the hooks and starting the latches open, and then swinging them on back 110 full open, ready for loop-engagement of the hooks.

3. The combination of a welt bar having latched hooks; and latch opening means including a stationary latch engaging element, and means for moving the welt bar relative to the element aforesaid to effect opening of the hook latches. 120

4. The combination of a welt bar having 120
latched hooks; and latch opening means in-
cluding a stationary latch engaging element,
and holder means for the welt bar operative
to effect opening of the hook latches by a 125
retractive-swing of the former relative to said
latch engaging element.

5. The combination of a welt bar having hooks with pivoted latches extending beyond the hook ends; and latch opening means including a stationary element with a beveled 130

edge for engaging the projecting ends of the hook latches and causing them to be opened incident to a retractive-downwardly-swinging movement imparted to the welt bar.

5 6. The combination of a welt bar having hooks with pivoted latches extending beyond the hook ends; and latch opening means including a latch engaging element, and sliding holder means, said latter means affording

10 fulcrum support for the welt bar along its rear edge with the ends of its hooks resting on the element aforesaid, so that, upon retraction of the holder means, the hooks drop off the element with incidental detention and

15 opening of their latches.

7. The combination in a flat knitting machine of a welt bar having latched hooks; guideways for the welt bar; and latch opening means including a latch engaging bar secured crosswise of welt bar guideways, and

20 slideable holder means on the guideways for moving the welt bar relative to the latch engaging bar.

8. The combination in a flat knitting machine of a welt bar having hooks with pivoted latches extending beyond the hook ends; guideways for the welt bar; and latch opening means including a latch engaging bar secured crosswise of welt bar guideways, and

30 slideable holder means on the guideways affording the welt bar fulcrum support along its rear edge with the ends of its hooks resting on the latch engaging bar, so that upon retraction of the holder means, the hooks drop off the latch engaging bar with incidental

35 detention and opening of the hook latches.

9. The combination in a flat knitting machine of a welt bar having latched hooks; guideways for the welt bar; and latch opening means including a latch engaging bar secured crosswise of welt bar guideways, slideable holder means on the guideways for the welt bar, and an actuating hand lever coordinated with the holder means for moving the

40 welt bar toward and away from said engaging bar to effect opening of the hook latches.

10. The combination in a flat knitting machine of a welt bar having hooks with pivoted latches extending beyond the hooked ends; guideways for the welt bar; and latch opening means including a latch engaging bar secured crosswise of welt bar guideways, slideable holder means on the guideways affording the welt bar fulcrum support along its

50 rear edge with the ends of its hooks resting on the latch opening bar, so that upon retraction of the holder means the hooks drop off the latch engaging bar with incidental

55 detention and opening of the hook latches,

60 and means to limit the sliding movement of the holder means in predetermining the action aforesaid.

11. The combination in a flat knitting machine of a welt bar having hooks with pivoted latches extending beyond the hook ends;

guideways for the welt bar; and latch opening means including a latch engaging bar secured crosswise of welt bar guideways, slideable holder means on the guideways affording the welt bar fulcrum support along its

70 rear edge with the ends of its hooks resting on the latch engaging bar, so that, upon retraction of the holder means, the hooks drop off the latch engaging bar with incidental

75 detention and opening of the hook latches, means to limit the sliding of the holder means in predetermining the action aforesaid, and a hand lever for actuating the holder means.

In testimony whereof, I have hereunto

80 signed my name at Philadelphia, Pennsylvania, this ninth day of January, 1930.

HAROLD F. PAGET.
